US00D697863S

(12) **United States Design Patent**
Beckerman et al.

(10) **Patent No.:** US D697,863 S
(45) **Date of Patent:** ** Jan. 21, 2014

(54) **FRAMELESS PHOTOVOLTAIC MODULE**

(71) **Applicant:** **Prism Solar Technologies, Inc.**,
Highland, NY (US)

(72) **Inventors:** **Wayne Beckerman**, Stone Ridge, NY
(US); **Jose E. Castillo-Aguilella**,
Tucson, AZ (US); **Paul S. Hauser**,
Tucson, AZ (US); **Kevin Randall**
Stewart, Niskayuna, NY (US); **Robert**
Davis, Lake Katrine, NY (US)

(73) **Assignee:** **Prism Solar Technologies, Inc.**, New
York, NY (US)

(**) **Term:** **14 Years**

(21) **Appl. No.:** **29/448,722**

(22) **Filed:** **Mar. 13, 2013**

(51) **LOC (10) Cl.** **13-02**

(52) **U.S. Cl.**

USPC **D13/102**

(58) **Field of Classification Search**

USPC D13/102, 101, 103, 107, 108, 110, 199;
136/243, 244, 245, 246, 251, 252, 259;

(57) **CLAIM**

The ornamental design for a frameless photovoltaic module, as shown and described.

DESCRIPTION

FIG. 1 is a perspective view of a frameless photovoltaic module showing our new design;
FIG. 2 is a top plan view thereof;
FIG. 3 is a bottom plan view thereof;
FIG. 4 is a first side elevational view thereof;
FIG. 5 is a second side elevational view thereof;
FIG. 6 is a third side elevational view thereof; and,
FIG. 7 is a fourth side elevational view thereof.
The broken lines shown represent unclaimed subject matter and form no part of the claimed design.
